UNITED STATES PATENT OFFICE.

EDWARD D. UTTERBACK, OF LUBBOCK, TEXAS.

MANIFOLD HEATER FOR AUTOMOBILES.

Application filed July 27, 1926. Serial No. 125,226.

This invention relates to devices for heating the manifolds of automobiles to thereby heat the fuel charge as it passes from the carbureter to the cylinders and the general object of the present invention is to provide a very simply constructed and easily applied device which may be attached over the manifolds of practically all cars but is particularly adapted to the manifolds of Ford cars and enclosing electric heaters whereby the manifold may be kept hot, thus saving gasoline in starting the engine and making the charge more effective when the engine is running.

15 A further object is to provide a construction of this character which is so arranged that the heating elements may be readily removed, replaced, or repaired.

My invention is illustrated in the accompanying drawings wherein:—

Figure 1 is a front elevation of a manifold with my heater applied thereto;

Fig. 2 is a section on the line 2—2 of Figure 1;

25 Fig. 3 is a section on the line 3—3 of Figure 1;

Fig. 4 is a section on the line 4—4 of Figure 3.

Referring to these drawings 10 designates 30 a metallic outer casing which is open at the bottom and is formed to provide a top plate 11, the front plate 12 and the rear plate 13. The end plates 14 are cut away as at 15 from the lower end of the end plate nearly 35 to the upper end thereof and the margins of this cut away portion are folded upon themselves to form guides to receive slides 16. The upper end of the cut away portion 15 is rounded and the upper end of each slide is 40 rounded so as to embrace the manifold A and fit thereon. The interior of this outer casing is preferably lined with asbestos so as to retain the heat within the casing.

Mounted within the casing and held there- 45 to by a plurality of bolts or screws 17 en- gaging the front plate, is a base 18 of in- sulating material having the end members 19 also of insulating material. Mounted upon the inner face of this base 18 by means 50 of binding screws are three or more heating coils 20 and mounted upon the end members 19 are a plurality of heating coils 21. These heating coils are connected to each other and to the battery of the automobile by conductors as will now be described so that when 55 the switch on the dash board is turned to

permit the passage of current through the coils, the coils will have become heated and will, of course, heat the manifold and the charge.

The coils 20 are each at one end connected to binding screws 22 which extend through the insulating base 18 and the opposite ends of the heating coils 20 are connected to binding screws 23 which also extend through the plate 18. The coils 21 are connected at their inner ends to binding screws 24 and at their outer ends to binding screws 25. Connected to all of the binding screws 23 is a lead 26 which extends from the battery of the car.

Extending from one of the binding screws 22 is an insulated conductor 27 which extends to one of the binding screws 24. A conductor 30 which is insulated engages one of the binding screws 25 and passes across the base 19 to one of the binding screws 23. From one of the binding screws 22 an insulated conductor 33 is connected to the binding screws 24 at the other end of the device, and the binding screws 25 at this end are connected by a conductor 34 to one of the binding screws 23. Sleeves 35 of insulating material preferably fit over the wires so as to fully space these wires from any chance contact with the metallic casing. The wire 26 runs to a battery (not shown).

In the operation of this device it will be obvious that when the switch is turned to permit the flow of current, the current will flow from the battery through the several coils of the heater and then back to the battery and that heat will be applied to the manifold on three sides thereof. The heating units practically encircle a portion of the manifold which insures the rapid application of heat. The interior of the body, being lined with asbestos, further insures the effectiveness of the device as a manifold heater. Set screws 17^a are disposed at the center of the base 18 and engage with the manifold, thus preventing short circuit by centering the heater.

While I have illustrated certain details of construction and arrangement of parts which I have found to be particularly effective in actual practice, I do not wish to be limited thereto as it is obvious that many changes might be made therein without departing from the spirit of the invention as defined in the appended claim.

I claim:—

A heater for an intake manifold compris-

ing a casing having an opening at its bottom side adapted to slidably receive the manifold and provided along its end walls with openings which register at their lower ends with the opening in the bottom side, the openings in the end walls terminating short of the top wall of the casing, slide members adapted to move along the lower portions of

the openings in the end walls, and heating elements located in the casing and arranged in groups which extend across the end walls and along the front wall of the casing.

5 In testimony whereof I hereunto affix my signature.

EDWARD D. UTTERBACK.
